UNITED STATES PATENT OFFICE

147,817

DESIGN FOR A TANK TRUCK

Willis W. Sampselle, Memphis, Tenn.

Application March 21, 1946, Serial No. 127,742

Term of patent 14 years

(Cl. D14—3)

To all whom it may concern:

Be it known that I, Willis W. Sampselle, a citizen of the United States of America, residing in Memphis, in the county of Shelby and State of Tennessee, have invented a new, original, and ornamental Design for Tank Trucks, of which the following is a specification, reference being had to the accompanying drawings, forming part thereof:

Fig. 1 is a side elevational view;

Fig. 2 is a top plan view; and

Fig. 3 a rear end elevation of my new design for a tank truck.

The opposite side of the truck is similar to that shown in Fig. 1.

I claim:

The ornamental design for a tank truck, substantially as shown and described.

WILLIS W. SAMPSELLE.
